TENT

John Sankus, Los Angeles, Calif.

Application July 30, 1932. Serial No. 626,725

1 Claim. (Cl. 135—3)

My invention relates to a tent of a substantial-
ly rectangular shape having sufficient head room
and without any posts obstructing the center of
the tent or the entrance door. It also relates
5 to a tent in which the various supporting posts
and framing elements may be readily discon-
nected for putting up and taking down the tent.

An object and feature of my invention is the
formation of a substantially rectangular tent with
10 four corner posts connected at the bottom by sill
bars and at the top by roof bars. The posts and
the sill and roof bars are disconnectably attached
by means of readily loosened and assembled
angles and bolts, using dowel pins for guidance
15 and for additional strength.

Another feature of my invention relates to
forming the sides and ends of the tent of sepa-
20 rate pieces of canvas which may be secured to
the posts and to the sills by readily disconnectible
fasteners.

Another feature of my invention relates to
forming the roof of the tent of netting so that
in fair weather the roof may be left entirely
25 open except for the netting.

Another feature of my invention relates to the
construction of a canvas shade at the front of the
30 tent, that is, the door end, this shade being de-
signed to be turned over the roof and form a cover
in rainy weather or to keep out the heat of the
sun. To run the rain off the roof, one side of
35 the tent is made lower than the other.

Another feature of my invention relates to con-
structing at least one of the ends of detachable
40 netting with a canvas detachable section which
may be secured in place or removed from inside
of the tent. Another detailed feature relates to
the construction of the door, this having a net-
ting suspended on the inside and a canvas door
45 forming the outside cover, which may be attached
to one of the corner posts at the free end.

My invention is illustrated in the accompan-
ying drawing, in which:

Fig. 1 is a perspective view of the tent.

Fig. 2 is a perspective view of one of the tent
45 posts and the roof bars.

Fig. 3 illustrates the attachment of the awning
to fixed posts.

Fig. 4 is a perspective view showing the con-
50 nection of an intermediate roof bar.

In my invention I employ four posts 11. These
are pointed at the bottom 12 and have a squared
top end 13, in which is fitted a center pin 14.
These posts at the top and adjacent the bottom
55 have an angle strap 15 formed of metal and se-

cured to the posts by screws 16. These straps
have perforations 17 for reception of a dowel.

At the bottom there are sill bars 18 connect-
ing all of the posts and at the top there are roof
bars 19. Each of these bars has its end cut square
60 to abut against the posts and each is provided
with a dowel pin 20 adjacent the end, the dowel
pin fitting into the perforations 17 in the metal
strap 15. Bolts 21 extend through the straps 15
and through the sill and roof bars, these bolts
65 preferably having a countersunk head 22 on the
outside and a thumb nut 23 on the inside to al-
low ready attaching and loosening of the connec-
tion of the sill and roof bars or beams.

The corner posts at the front are provided with
70 screw eyes 24 on the two outside faces and the
two back posts are provided with screw eyes on
one of the outside and one of the inside faces
at the end. The sills and the roof bars at the two
sides and the back are provided with screw eyes
75 on the vertical face. At the front end the sill
is provided with screw eyes on the front vertical
face and the roof bar on the vertical outside face
and top face. Two of the side posts are prefer-
ably shorter than the other posts on the oppo-
80 site side to give a slope for running rain water
off the roof.

The roof is preferably formed of netting 25;
such netting is formed with a band 26 at the edge,
35 with grummets 27 through this binding. The roof
netting is stretched over the roof bars and secured
to the eyes by inserting the grummets over the eyes
and then rotating the eyes to prevent them from
pulling out. The pins 14 at the top of the posts
40 also fit in grummets on the roof netting. Thus,
the roof netting is turned downwardly over the
outside vertical face of each of the roof bars. On
the end at the inside, a net 28 is used and secured
45 to the eyes on the inside vertical face of the posts
and on the inside vertical face of the sill and roof
bar. This allows the netting to be put on or
taken off from the inside of the tent. In addi-
50 tion, the end canvas 29 is cut the shape of the
back end of the tent. All of the canvas covers
are provided with grummets 30 adjacent their
margin and these are secured to the same eyes
holding the net 28. The two opposite sides 31
55 and 32 are formed of separate pieces of canvas,
each having grummets and these strips of can-
vas are attached to the two side posts and the
bottom sill and top roof rail by the eyes on the
60 vertical outside faces of the posts and the rails.
The front end 33 is formed of a strip of canvas
also having grummets secured to the front ver-
tical faces of the two front posts, the sill, and

the cross roof rail. A section of this may be unfastened and form a door 34. This front end is also provided with a net 35 which may be the same as the net 28 at the back end of the tent. 5 Thus, when the tent is being more or less constantly entered may be loosened at one side and the bottom to allow ready passage in and out of the tent, but at night the netting may be securely attached to keep out insects.

10 The combination roof and awning designated 36 comprises a strip of canvas provided with grummet along the edges and this is secured to the pins 14 on the top of the posts and at one end when it is desired to use it as a mounting to the 15 roof front cross rail. A pair of posts 37 are sunk in the ground. These posts may be braced by guy ropes 38, also there may be guy ropes 39 at the rear end of the tent. The awning is illustrated as having a flap 40 secured to eyes 41 on 20 the posts. These posts also have hooks 42 which catch in the grummet on the awning top section 36. This construction forms a tent with a net top and a canvas awning in front. However, this awning may be turned back over the roof and at- 25 tached to the eyes extending along the top face of the front roof beam and the eyes along the vertical

face of the back cross roof bar and the two side roof bars. This construction makes a water tight cover for the top of the tent and in rainy weather drains the water off the roof.

If desired, intermediate roof bars 43 may be 80 connected between the side roof bars. The connection illustrated uses dowels 44 on the end of the intermediate bars fitting into sockets 45 on the side bars. This gives an additional support to the roof or canvas, reducing the sagging. 85

Various changes may be made in the details of construction without departing from the scope of the invention as defined by the appended claim.

I claim:

In a tent, a tent frame having four rectangular posts, each with a sharp point, right angular straps secured to each post extending beyond the sides of the posts, sill and roof bars connected to the straps by bolts, each strap having a pair of perforations, dowels extending through the perforations into each of said bars, each of the roof bars having a socket, and an intermediate roof bar having a dowel at its end fitted into said sockets.

JOHN SANKUS.
